UNITED STATES PATENT OFFICE.

BRYANT BANNISTER, OF WILKINSBURG, PENNSYLVANIA.

FEED-WATER REGULATOR.

1,121,596.

Specification of Letters Patent. Patented Dec. 15, 1914.

Application filed June 13, 1914. Serial No. 844,849.

To all whom it may concern:

Be it known that I, BRYANT BANNISTER, a citizen of the United States, residing at Wilkinsburg, in the county of Allegheny and State of Pennsylvania, have invented a new and useful Feed-Water Regulator, of which the following is a specification.

My invention relates to feed water regulators used in regulating and controlling the flow of feed water into steam boilers and in maintaining the water level in the steam boiler at the required height or between the high level and low level to be maintained in the boiler.

One object of the invention is to provide a feed water regulator of improved construction having novel means whereby a continuous flow of feed water into the boiler is effected and the level of the water in the boiler is maintained within narrow limits defining the high and the low water levels.

Another object of my invention is to provide a feed water regulator having improved means whereby the quantity of water supplied to the boiler is increased and reduced with the increases or reductions in the amount of steam produced by the boiler irrespective of the pressure of the steam.

Still further objects of the invention will appear hereinafter as the invention is more fully described in the specification and more particularly pointed out in the appended claims.

Referring to the drawings, forming part of this specification, Figure 1 is an elevation, partly in section, showing a feed water regulator constructed and arranged and applied for use on a steam boiler in accordance with my invention. Fig. 2 is a sectional elevation of the feed valve by which the flow of feed water into the boiler is regulated and controlled. Fig. 3 is a detail elevation of the pilot valve forming part of this invention.

In the accompanying drawings, the numeral 2 designates a steam boiler which is connected, by pipes 4 and 5, to the top and bottom of the float column 6 of the feed water regulator forming my invention, above and below the water level 3 of the boiler. The float column 6, which is provided with a water gage 7 of the usual construction, is connected, through an opening in the head 8 on its upper end, by the pipe 9, with the lower end of the differential cylinder 10, forming part of the valve disk operating mechanism for the valve 11. The

valve 11 which is in and forms part of the feed water line 43 leading to the steam boiler 2 from a feed water heater 44, regulates and controls the flow of feed water into the boiler. The opening in the head 8 for the end of the pipe 9 also has a pilot valve 12 secured therein, this valve being on the inside of the float column 6, and having a flap 13 pivoted therein. The flap 13 is connected to one end of the lever 14 and pivotally connected adjacent to its upper end to the outer swinging end of the lever 14, is the stem 15 on the hollow ball forming the float 16 within the float column 6. The flap 13 in the pilot valve is positioned so as to be partly open when the float is in the position shown.

The lever 14 for the flap valve in the float column 6 is provided with a guide 17 having shoulders 18 and 19 forming stops by which the upward and downward movement of this lever and the float 16 connected thereto is limited and the valve flap 13 is held in widely open and in closed positions.

The valve 11, by which the flow of water through the feed water line to the boiler 2 is regulated, is provided with a seat 20^a and a frusto-conical nozzle 20 extending above the seat in which a tapered valve disk 21 is located. The lower side of the valve disk 21 has a stem 22 which extends downwardly through the spider 23 in the valve body to form a guide for the valve disk 21. The differential cylinder 10 on top of the feed valve is provided with a differential piston 24. The large end of the piston 24 is provided with packing rings 25 and its small end with packing rings 26 of usual and known construction and the large end 27 of the differential cylinder 10, which is made in sections 28 is provided with a bronze bushing or lining 29. At one point in this annular lining 28 a narrow vertically extending slot 29 is formed, which is narrow in width compared to its length and which affords means of communication between the interior of the large end 27 of the differential cylinder 10, and the port opening 30 into which one end of the pipe 31 is connected. At the lower end of the differential piston beneath the piston, a second inlet 32 is formed leading into the cylinder which is connected to one end of the pipe 9 leading from the upper end of the float column 6.

The upper or small end of the differential piston 24 projects upwardly into the small upper end of the vertically extending dif-

ferential cylinder 10, and a stem 36 is connected at one end to the piston 24 and extends upwardly through a stuffing box 34 and gland 35 on the upper end of the cylinder, to provide means for manually lifting the piston 24 and, through the connecting stem 36, the valve disk 21 in the valve body 11.

A stuffing box 37 and plug forming a gland 38 are provided in the head 39 which separates the body 11 of the feed valve from the lower end of the differential cylinder 10, through which the stem 36 extends.

The pipe 9 leads from the upper end 15 of the float column 6 to the lower end of the differential cylinder 10 and the pipe 31 connected to the port 30 in the large end of the cylinder 11 leads to an exhaust line, connected at its other end to a feed 20 water heater, or other source of low fluid pressure so as to subject this end of the cylinder, beneath the piston 24, to the pressure of the steam in the exhaust line.

Connected to a T 40 on the pipe 4 which 25 connects the upper end of the float column 6 with the boiler 2 is a small pipe 41 by which the small upper end of the differential cylinder 10 above the piston 24 is connected to the float column 6 and boiler 30 2. The opening 42 in the lining 28 connects the cylinder 10 above the upper face of the large end of the piston 24 to permit the escape into the port 30 of fluid pressure collecting above the large end of the piston 35 24.

The operation of my improved apparatus will now be described.

The water level in the float column 6 is always the same as the level in the boiler 40 2 and rises and falls with fluctuations in the height of the water in the boiler. When the water level in the float column falls, the float 16 drops and in dropping, opens the flap 13 of the pilot valve 12 so as to admit 45 more and more steam into the pipe 9 leading from the float column 6 to the under side of the large piston 24 in the differential cylinder 10. This causes the pressure under the piston 24 to increase until it becomes great enough to overcome the pressure of steam on the upper small end of the piston and move the piston upward. The small end of the piston 24 which operates in the small end of the cylinder is at all 50 times connected by the pipe 41 to the steam boiler 2 and float chamber 6 so as to always have full boiler pressure operating thereon. As the water level is lowered in the boiler 2 the increased supply of steam to the under side of the large end of the differential piston 24 moves the piston upwardly in the cylinder 10 and in moving upward uncovers more and more of the vertical slot 29 through the wall of the bronze bushing or 55 lining 28 in the large end of the cylinder

10. This increase in the size of the slot 29 permits steam in greater and increasingly greater quantities to escape through the port 30 into the pipe 31 and through this pipe into the steam exhaust line leading to the 70 feed water heater or other source of low pressure. In this way the piston 24 will be caused to move upwardly just far enough to relieve the pressure on the large end of the piston 24 to an extent sufficient to counter- 75 balance the effect of the higher pressure on the lesser area of the small end of the piston. The upward movement of the piston 24, through the stem 36, lifts the valve disk 21 in the frusto-conical nozzle 20 within 80 the body of the valve 11. When this disk is raised from the valve seat 20° in this way, the valve 11 is opened to an increasingly greater extent so that more and more water is admitted from the feed water line 85 through the outlet opening in the valve 11 to the boiler 2. The float 16 will automatically drop until the disk 21 of the feed valve is raised sufficiently to increase the feed water supply enough to maintain the water 90 level in the boiler. The float will then slowly move up and down, within a narrow range of travel, with the slight rise and fall of the water from the level 3 in the boiler 2, so as to remain practically stationary. Should the evaporation of water in the boiler drop off suddenly, the water will rise above the level 3. This increase in the height of the water will cause a similar rise of the water in the float column 6. 100 The float 15 will lift as the height of the water increases and in so doing will more nearly and, with sufficient change in the water level, entirely close the flap valve 12 in the column 6 and lessen or shut off the 105 steam supply to the pipe 9 which extends from the upper end of the float column 6 to the under side of the piston 24. The partial closing of the pilot valve 12 reduces the quantity of steam supplied 110 through the pipe 9 to the under side of the large piston, which will then be forced downwardly by the action of the boiler pressure on the upper small end of the differential piston 24. The position of the piston in 115 the lower large end of the cylinder 10 will be such as to expose just enough of the slot 29 in the lining or bushing 28 to maintain the pressure necessary to balance the effect of the boiler pressure on the upper small 120 end of the piston. Downward movement of the piston 24 causes the valve disk 21 to move downwardly and partially close the valve 11 so as to lessen or reduce the flow of feed water therethrough into the boiler and prevent undue rise in the level of the water in the boiler, that would otherwise take place, by reason of the lessened amount of evaporation of water in the boiler. 125

The advantages of my invention will be 130

apparent to those skilled in the art. The apparatus is simple and is easily kept in repair. By its use the water is maintained in the boiler at a practically constant level and excessive changes in the water level maintained in the boiler are prevented and overcome.

Modifications in the construction and arrangement of the parts forming my novel apparatus may be made without departing from my invention as defined in the appended claims.

I claim:

1. A feed water regulator, comprising in combination a float column having steam and water connections to a steam boiler, a valve in the feed water line to said boiler, a differential cylinder having a piston operatively connected to the disk of said valve, means connecting the steam end of the float column with the cylinder at the large end of the piston therein, said means having a pilot valve operatively connected to the float in said column, means connecting the steam end of said column with the cylinder at the small end of the piston, and a port in the large end of the differential cylinder to relieve the steam pressure on the large end of said piston, said port being covered and uncovered by movement of the piston in said cylinder.

2. The combination with a steam boiler and a feed water heater, having a feed water line connected to said boiler, of a feed water regulator, comprising a float column having steam and water connections to a steam boiler, a valve in the feed water line to said boiler, a differential cylinder having a piston operatively connected to the disk of said valve, means connecting the steam end of the column with the cylinder at the large end of the piston therein, said means having a pilot valve operatively connected to the float in said column, means connecting the steam end of said column with the cylinder at the small end of the piston, a port opening connected to the feed water heater, and a slot in the wall of said cylinder connecting the cylinder and port, said slot being positioned to be covered and uncovered by the large end of said piston.

3. The combination with a steam boiler and a feed water heater, having a feed water line connected to said boiler, of a feed water regulator comprising a float column having steam and water connections to a steam boiler, valve in the feed water line to said boiler, a differential cylinder having a piston operatively connected to the disk of said valve, means connecting the steam end of the column with the cylinder at the large end of the piston, said means having a pilot valve operatively connected to the float in said column, said float being arranged to lift in closing the pilot valve, means con-

nnecting the steam end of said column with the cylinder at the small end of the piston therein, a port opening to the feed water heater, and a slot in the wall of said cylinder connecting the cylinder and port, said slot being positioned to be covered and uncovered by the large end of said piston.

4. The combination with a steam boiler and a feed water heater, having a feed water line connected to said boiler, of a feed water regulator, comprising a float column having steam and water connections to a steam boiler, a valve in the feed water line to said boiler, a differential cylinder having a piston operatively connected to the disk of said valve, means connecting the steam end of the float column with the cylinder, at the large end of the piston therein, said means having a pilot valve operatively connected to the float in said column, said float being arranged to lift in closing the pilot valve, means in said column for limiting the movement of the float therein, means connecting the steam end of said column with the cylinder at the small end of the piston, a port opening connected to a feed water heater, and a slot in the wall of said cylinder connecting the cylinder and port, said slot being positioned to be covered and uncovered by the large end of said piston.

5. A feed water regulator for boilers comprising a float column connected to the boiler above and below the established water level thereof, a float controlled pilot valve in said float column, a valve controlling the flow of feed water to the boiler from a feed water line, a differential cylinder having a differential piston operatively connected to the valve disk of the valve on the feed water line, means connecting the small end of said cylinder to the boiler and float column above the water level therein, means connecting the outlet on said pilot valve to the large end of said cylinder, and a lengthwise vertical slot in the wall of the large end of said cylinder and connected to a source of low pressure, said pilot valve being actuated to vary the supply of steam passing from the float column into the large end of said cylinder and the large end of said piston covering and uncovering the vertical slot in the side wall of the cylinder to maintain equilibrium on the opposite ends of the piston and vary the flow of steam through the cylinder into the source of low pressure, to thereby move the valve disk and decrease or increase the flow of water through said feed water valve into the boiler.

6. A feed water regulator, comprising in combination a float column having steam and water connections to a steam boiler, a valve in the feed water line to said boiler, a differential cylinder having a piston operatively connected to the disk of said valve, means connecting the steam end of the col-

umn with the cylinder at the large end of the piston therein, said means having a pilot valve operatively connected to the float in said column, means connecting the steam end of said column with the cylinder at the small end of the piston, a port opening connected to a source of low pressure, and a slot in the wall of said cylinder connecting the cylinder and port, said slot being positioned to be covered and uncovered by the large end of said piston.

7. A feed water regulator comprising in combination a float column having steam and water connections to a steam boiler, a valve in the feed water line to said boiler, a differential cylinder having a piston operatively connected to the disk of said valve, means connecting the steam end of the column with the cylinder at the large end of the piston, said means having a pilot valve operatively connected to the float in said column, said float being arranged to lift in closing the pilot valve, means connecting the steam end of said column with the cylinder at the small end of the piston therein, a port opening to a source of low pressure, and a slot in the wall of said cylinder connecting the cylinder and port, said slot being positioned to be covered and uncovered by the large end of said piston.

8. A feed water regulator, comprising in combination a float column having steam and water connections to a steam boiler, a valve in the feed water line to said boiler, a differential cylinder having a piston operatively connected to the disk of said valve, means connecting the steam end of the float column with the cylinder, at the large end of the piston therein, said means having a pilot valve operatively connected to the float in said column, said float being arranged to lift in closing the pilot valve, means in said column for limiting the movement of the float therein, means connecting the steam end of said column with the cylinder at the small end of the piston, a port opening connected to a source of low pressure, and a slot in the wall of said cylinder connecting the cylinder and port, said slot being positioned to be covered and uncovered by the large end of said piston.

9. A feed water regulator for boilers comprising a float column connected to the boiler above and below the established water level thereof, a float controlled pilot valve in said float column, a valve controlling the flow of feed water to the boiler from a feed water line, a differential cylinder having a differential piston operatively connected to the valve disk of the valve on the feed water line, means connecting the small end of said cylinder to the boiler and float column above the water level therein, means connecting the outlet on said pilot valve to the large end of said cylinder, and a lengthwise vertical slot in the wall of the large end of said cylinder and connected to a source of low pressure, said pilot valve being actuated to vary the supply of steam passing from the float column into the large end of said cylinder and the large end of said piston covering and uncovering the vertical slot in the side wall of the cylinder to maintain equilibrium on the opposite ends of the piston and vary the flow of steam through the cylinder thereby move the valve disk and increase or decrease the flow of water through said feed water valve into the boiler.

10. A feed water regulator, comprising in combination a float column having steam and water connections to a steam boiler, a valve in the feed water line to said boiler, a differential cylinder having a piston operatively connected to the disk of said valve, means connecting the steam end of the column with the cylinder at the large end of the piston therein, said means having a pilot valve operatively connected to the float in said column, means connecting the steam end of said column with the cylinder at the small end of the piston, a port opening and a slot in the wall of said cylinder connecting the cylinder and port, said slot being positioned to be covered and uncovered by the large end of said piston.

In testimony whereof, I have hereunto set my hand.

BRYANT BANNISTER.
